UNITED STATES PATENT OFFICE.

HENRY C. BERRYMAN, OF BROOKLYN, NEW YORK.

SHIRT.

1,107,021.

Specification of Letters Patent. Patented Aug. 11, 1914.

Application filed November 15, 1911. Serial No. 660,491.

To all whom it may concern:

Be it known that I, HENRY C. BERRYMAN, a citizen of the United States, residing at Brooklyn, in the county of Kings and State 5 of New York, have invented new and useful Improvements in Shirts, of which the following is a specification.

This invention relates to shirts, and more especially to shirts carrying certain new and 10 useful attachments, such as suspensors or other appliances beneficial for medical or surgical purposes, as will be more fully described in the following specification, set forth in the claim and illustrated in the 15 drawings, wherein:—

Figure 1 is a front view of a shirt partly broken away showing the improvement applied thereto. Fig. 2 is a front view of a shirt as it appears from the outside. Fig. 3 20 shows a modified form of arrangement.

In the use of articles for surgical and medicinal purposes and adapted to be worn by the patient, the application of these 25 appliances is somewhat difficult on account of the use of strips and other attachments.

This invention provides for carrying and locating certain surgical devices in a convenient and comfortable manner as shown in the drawings and where it will be seen that 30 an ordinary shirt is used made of any desired material and having woven within its front a suspensor 5 of the usual type and which may be also used for carrying medicines and healing preparations for the use of 35 the wearer. While a suspensor is thus shown, it is obvious that the device may be so modified as to use it for the purposes and in the manner above specified, and when thus located the device is given the proper 40 support and hung from the shoulders, doing away with the serious inconvenience experienced by strapping or otherwise securing the device around the body of the wearer.

In the modified form shown in Fig. 3, the device is applied to a coat shirt and made 45 integral with one side thereof. The outer end or flap 6 of the suspensor is carried over to the other side of the shirt and buttoned thereto. This provides for the ready and convenient arrangement of the suspensor 50 when applying to a shirt of this character. It is preferable, however, that no buttons or other attachments be used on account of their irritating nature. The front 55 of the shirt presents its usual appearance and is provided with nothing which will irritate the wearer, and the suspensor may be secured at the desired point either by weaving it with the balance of the shirt or stitching same to the shirt as desired. 60

It is obvious that the shirt may be otherwise modified in this construction to provide for a more comfortable or cheaper arrangement of the buttoned parts without departing from the essential features above 65 described.

What I claim as new and desire to secure by Letters Patent is,—

In combination with a shirt, a pouch having an opening, an edge portion of the 70 pouch being attached with the shirt at the inner side thereof, the pouch also having a free edge portion which lies between the inner side of the shirt and that portion of the pouch which is provided with the opening the portions of the pouch being so proportioned that the said opening normally lies opposite the inner side of the shirt and between the free and attached edge portions of the pouch. 75

In testimony whereof I affix my signature in presence of two witnesses.

HENRY C. BERRYMAN.
